UNITED STATES PATENT OFFICE.

ELI BEGHTEL, OF HUNTINGTON, INDIANA.

MAIL-CONVEYER.

SPECIFICATION forming part of Letters Patent No. 737,320, dated August 25, 1903.

Application filed March 19, 1903. Serial No. 148,633. (No model.)

To all whom it may concern:

Be it known that I, ELI BEGHTEL, a citizen of the United States of America, residing at Huntington, in the county of Huntington and State of Indiana, have invented certain new and useful Improvements in Mail-Conveyers, of which the following is a specification.

This invention relates to conveyers; and it is designed for use particularly in rural districts for conveying mail from the postal road to a house, and vice versa.

The objects of the invention are, first, to produce a novel receptacle for mail or other matter to be carried; second, to provide novel means for supporting and propelling the receptacle; third, to provide novel means for retaining the supporting and propelling means in certain relation throughout the length of the conveyer.

Finally, an object of the invention is to produce a conveyer of the character noted which will possess advantages in points of simplicity, efficiency, and durability, proving at the same time rapid in action and comparatively inexpensive of manufacture.

With the foregoing and other objects in view the invention consists in the details of construction and in the arrangement and combination of parts to be hereinafter more fully set forth and claimed.

In describing the invention in detail references will be had to the accompanying drawings, forming part of the specification, wherein like characters denote corresponding parts in the several views, and in which—

Figure 1 is a view in elevation, illustrating a conveyer embodying the invention. Fig. 2 is a detail view illustrating a bracket and the wire supported thereby. Fig. 3 is a sectional view in the line 3 3 of Fig. 1.

In the drawings, A indicates a series of posts terminating at the side or near a road traversed by a rural mail-carrier and near or at a house where mail is to be delivered.

The end posts have suitable brackets B, with spindles C, on which wheels D are mounted, said wheels having peripheral grooves E, in which a cable F travels as the wheels are rotated. One or both wheels may have a hub G, provided with teeth H, and gear-wheel I, mounted on a stud J, meshes with the teeth H, and as the gear-wheel is

rotated motion is imparted to the wheels D through the cable F. The gear-wheel is moved by an operator manipulating the handle K. 55 By having a gear-wheel at each end the postman may send the receptacle or the occupants of the house may operate the conveyer from their end.

The intermediate posts have brackets a, 60 with upturned ends b, said ends being recessed to form seats c for the supporting-wire d, which extends from one end post to the other. Metallic strips e, preferably of copper, are riveted to the brackets and are bent down 65 over the ends to retain the wire in the seat. The strips are bent under the brackets and are secured by wire f, wrapped around the brackets.

A receptacle 1 has a hanger 2 secured to its 70 top, said hanger having a grooved wheel to travel on the supporting-wire d from one end post to the other and return. The receptacle has one end beveled and provided with a door 3, which opens inwardly. The door is hinged 75 at the top, and its bottom has a weight 4, whereby said door is retained closed by gravity. Mail may be inserted by pushing against the door, passing the mail within, and permitting the door to automatically close. Owing 80 to the beveled end and door the interior of the receptacle is protected against the entrance of water and the mail may be inserted with one hand.

The cable F is guided by arms 5, which have 85 recesses 6, in which the cable travels. These recesses may have antifriction-rollers 7 to facilitate the movement of the cable in the guides.

After the mail has been deposited at either 90 end of the line the receptacle may be propelled along supporting-wire through medium of the gear-wheels, as heretofore described. The operation, it is thought, will be understood from the foregoing description, and it is noted 95 that changes in the proportions and details of construction may be resorted to without departing from the scope of the invention.

Having fully described the invention, what I claim as new, and desire to secure by Letters 100 Patent, is—

1. In a conveyer suitable posts, wheels mounted on studs secured to the posts, a cable operating over the wheel, means for ro-

tating the wheels, a supporting-wire, a receptacle having a beveled end, a weight-door for the beveled end, a hanger for the receptacle and the wheel journaled in the hanger adapted to run on the supporting-wire, as and for the purpose described.

2. In a conveyer, a series of posts, wheels mounted on studs secured to the posts, a cable operating over the wheels, means for rotating the wheels, a receptacle having a beveled end, a door for the beveled end, a weight for automatically closing the door, brackets secured to the posts, said brackets having

upturned ends with recess - forming seats, supporting-wire resting in the seats, metallic strips riveted to the ends of the bracket and turned over the supporting-wire, and binding-wire for securing the strips to the bracket as and for the purpose described. 15

In testimony whereof I affix my signature, 20 in the presence of two witnesses, this 27th day of February, 1903.

ELI BEGHTEL.
